Merchant and Leger

UNITED STATES PATENT OFFICE.

OLOF S. BURMAN, OF MINNEAPOLIS, MINNESOTA.

LAUNDRY-TRAY FAUCET.

Application filed February 15, 1922. Serial No. 536,840.

To all whom it may concern:

Be it known that I, OLOF S. BURMAN, a citizen of the United States, residing at Minneapolis, in the county of Hennepin 5 and State of Minnesota, have invented certain new and useful Improvements in Laundry-Tray Faucets; and I do hereby declare the following to be a full, clear, and exact description of the invention, such as 10 will enable others skilled in the art to which it appertains to make and use the same.

My present invention provides an extremely simple and highly efficient faucet having means for detachably securing the 15 same to a two-compartment laundry tray or tub, and which faucet has a swinging nozzle for delivery into either compartment of such tray. Generally stated, the invention consists of the novel devices and combinations of devices hereinafter described and 20 defined in the claims.

As a distinctive feature, this faucet is provided with a pair of depending rigidly secured legs that are adapted to straddle the 25 partition of a laundry tray and are provided at their lower ends with clamping devices for rigidly clamping the same to the tray, and which faucet, when thus attached, will support the swinging nozzle positioned for 30 delivery into either compartment of the tray.

In the accompanying drawings, which illustrate the invention, like characters indicate like parts throughout the several views.

35 Referring to the drawings:

Fig. 1 is a view chiefly in elevation but with some parts sectioned showing the improved faucet applied to a laundry tray having two compartments; and

40 Fig. 2 is a side elevation of the faucet, the tub being sectioned on the line 2—2 of Fig. 1.

The laundry tray or tub 3 has two compartments located on opposite sides of a dividing partition 4. The faucet, although provided with but one nozzle, to wit: a laterally swinging nozzle, is, nevertheless, of the general type known as a double faucet in that it receives hot and cold water, respectively, from supply pipes 5 and 6. These pipes 5 45 and 6 connect into end chambers 7 that are connected to the tubular faucet body 8 through ports normally closed by valve heads 9 on the ends of valve-operating stems 10, which latter have the customary threaded 50 engagement with stuffing boxes 11 applied to tubular end extensions 12 of the faucet.

At its central portion, the faucet body 8 has a depending nipple 13 to which the laterally swinging faucet 14 is swiveled by means of a packed stuffing box 15. On opposite sides 60 of the nipple 13, the faucet body 8 has depending threaded studs 16 onto which the internally threaded upper ends of faucet-supporting legs 17 are tightly screwed. These legs 17, at their lower ends, are formed with 65 prongs 18 that embrace the edge of the tray 3. These supporting legs 17 are positioned one on each side of the partition 4, so that they support the faucet 14 with its swivel axis above said partition and with its free end 70 positioned to swing from one side to the other of the partition for delivery into either compartment of the tray. The outer ears of the prongs 18 are provided with set screws 19, which, when tightened against the tray, 75 tightly hold the legs anchored to the tray and, hence, firmly support the faucet in the working position above described. The legs 17, when screwed onto the studs 16, become rigid or immovable parts of the faucet body 80 and, hence, rigidly and definitely fix the faucet in working position.

The provision of the detachable supporting legs 17 is of great importance, for two reasons. The faucets are each packed in separate boxes, the legs 17 and the swinging faucet 14 being first detached, permitting the utilization of a much smaller packing receptacle. It is clear that the purchaser, 85 without any great mechanical ability, may readily assemble the legs and the faucet. Furthermore the provision of the screw-threaded connections between the legs 17 and the studs 16, permits the adjustments necessary to vary the distance between the 90 studs and the prongs 18, permitting the attachment of the faucet to tubs of varying heights.

In certain instances it is not desirable to connect the faucet directly to the tub, but to 100 support it above the tub by overhead pipes. Under such circumstances a hose will be connected to the swinging faucet, and it becomes necessary that the legs 17 be detached to permit the faucet to swing completely 105 around in a horizontal plane, so as to feed several tubs. With the hose thus attached it may be inserted into any one of several compartments or tubs, or into an adjacent washing machine, or directed to the floor. 110

Obviously, either cold or hot water or a mixture of the two may be supplied into

either compartment of the tub. The faucet described is of simple construction and may be manufactured at relatively small cost and, at the same time, is highly efficient for all of the purposes had in view. It has the advantage that it may be very quickly applied to a laundry tray or tub.

What I claim is:

1. A hot and cold water faucet having a laterally swinging nozzle and provided with a pair of laterally spaced legs detachably secured to the body of the faucet at points above the swinging plane of the latter.
2. A hot and cold water faucet having a laterally swinging nozzle, and a pair of laterally spaced independent legs detachably and adjustably but rigidly secured to the body of the faucet and provided at their lower ends with prongs for engagement with a two-compartment laundry tray on opposite sides of its partition.
3. A hot and cold water faucet having a

laterally swinging nozzle, and a pair of laterally spaced depending screw-threaded studs, and a pair of independent legs having at their upper ends screw-threaded engagement with said studs and having at their lower ends prongs for engagement with a two-compartment laundry tray on opposite sides of its partition.

4. A hot and cold water faucet comprising a body having a laterally swinging nozzle, an externally screw-threaded depending stud on each side of said nozzle, and a supporting leg on each side of said nozzle, each leg being hollow and internally screw-threaded at one end and adapted for detachable and adjustable engagement with one of said studs, and provided with clamping members at its other end for detachable connection to a laundry tray.

In testimony whereof I affix my signature.

OLOF S. BURMAN.
